FLUID PRESSURE CYCLING SYSTEM

Jurg A. Senn, Milwaukee, Wis.

Application November 2, 1945, Serial No. 626,342

21 Claims. (Cl. 200—83)

1

This invention relates to cycling systems and particularly to devices of this class which supply current to an electric heater in the increments necessary to replace the heat dissipated by a body heated by such heater. In supplying current to surface burner units of electric ranges, for example, it has been proposed to provide a temperature sensitive or feeler element centrally of the burner coil and in contact with the bottom of the pan to "feel" the temperature thereof. The heat received by the feeler unit is converted to fluid pressure acting upon a remotely located pressure diaphragm which serves to adjust the position of a pair of cooperating switch elements with respect to a switch-opening cycling cam. A single cycling cam may be arranged to actuate several sets of switch elements spaced thereabout, four for example, corresponding to the number of surface plates of the usual electric range. This grouping of the switch arms for the respective heater plates about the central cycling cam is disadvantageous and difficult to attain, however, where only the customary long and relatively narrow range switch panel is available.

An object of this invention is to provide a cycling system for electric heaters in which the cycling source is fluid-coupled to the switch cycled thereby and hence may be located remote from the latter.

An additional object of the present invention is to provide a cycling system for electric heating plates in which both the feeler element and the cycling cam exert additive fluid pressure upon one or more expansible, switch-moving diaphragms.

Another object is to provide a cycling system for electric heaters in which the feeler element, cycling source and switch-actuating diaphragm are connected by a common, liquid-filled conduit.

Another object is to provide a cycling system for electric heaters in which the feeler element and cycling source are fluid-coupled to respective switch-actuating diaphragms.

A further object is to provide a cycling system for electric heaters in which the cycling switch movement results from the periodic electric heating of the fluid within a sealed diaphragm by a resistance means located adjacent thereto.

Another object is to provide a switch for cycling systems as described in which the zero adjustment is effected by shifting a portion of the switch lever engaged by the range cam thereby effecting a considerable simplification in switch construction.

2

A further object is to provide a switch for cycling systems as described characterized by flexible, hinge-mounted switch arms thus eliminating lost motion, friction and misalignment of parts.

Other objects and advantages of the invention will appear as the description thereof proceeds.

Reference is now made to the drawing wherein Fig. 1 is a vertical sectional view of one form of my invention and is taken on the line 1—1 of Fig. 2;

Fig. 2 is a top view of the switch shown in Fig. 1 and is taken on the line 2—2 of Fig. 1;

Fig. 3 is a modification of the construction of Fig. 1 and shows the replacement of the cycling cam 15 by an electrically heated sealed diaphragm;

Fig. 4 is a vertical sectional view of a simplified form of fluid actuated cycling switch according to the systems of Figs. 1 and 3 and taken on the line 4—4 of Fig. 5; and

Fig. 5 is a top view of the switch of Fig. 4 with the cover 67 removed.

Fig. 6 is a vertical sectional view of the form 25 of my invention shown in Fig. 1 as modified by the construction shown in Fig. 3, taken on line 6—6 of Fig. 7, and Fig. 7 is a sectional elevation taken on the line 7—7 of Fig. 6.

Referring now to Fig. 1 there is indicated at 30 1 a switch housing having a bottom wall 2 through which extends a threaded nipple 3 held in place by a nut 4 thereon. A flexible diaphragm assembly 5 including an upper element 5a and a similar lower element 5b peripherally united thereto is secured to the top of the nipple 3 as by welding and is centrally apertured as shown to receive liquid under pressure through the bore of the nipple. A follower spring 6 is secured by a screw 7 to a block 8 which may be mounted on the housing in any suitable manner and carries on its opposite end a contact block 9 for transmitting the pressure of the diaphragm element 5a to the switch mechanism properly described hereinafter. The bore of nipple 3 is suitably 35 united to a conduit 10 which has a lateral portion 10a terminating in a constant volume heat detector or feeler member 11 which in range application is usually placed at the center of the burner plate and in spaced, surrounded relationship with the latter.

Thus, as the temperature of the pan contacting the feeler member 11 is raised, the fluid therein will be forced through conduit 10 into the diaphragm 5 which is expanded thereby to move the block 9 upwardly. Another branch

10b of the conduit **10** connects to a bored nipple **12** serving as a mount for a variable volume liquid reservoir such as a centrally apertured, flexible diaphragm **13** which is adapted to be filled with the liquid from conduit **10b**. A contact button **14** is mounted centrally of the outer element of diaphragm **13** and is adapted to be laterally displaced by the throw of an eccentric cam **15** mounted on a shaft **16** which is preferably driven at a uniform speed by a suitable motor (not shown) to periodically force the liquid out of diaphragm **13** and into diaphragm **5** to thereby move the block **9** upwardly against the influence of follow-up spring **6**.

A pin **11** extends transversely of the switch housing **1** and through the side walls **18** thereof and constitutes a fulcrum for an angular lever block **19** preferably of insulating material and having an arm **19a** adapted to contact an adjustable stop preferably in the form of a screw as **20** threaded through a block **21** fixed to the housing **1** by a screw **22**. Lever block **19** serves as a rocking support for a pair of spaced, parallel switch arms **23** secured to the block by screws **23a** and having contacts **24** on the ends thereof adapted to be bridged by a bar contact **25** secured by rivet **25a** to the end of a generally triangular lever **26** having parallel side walls **26a** through which extends the shaft **17** as a pivot.

A generally triangular main lever **28** is provided below the lever **26** and includes side walls **28a** of sufficient width to eclipse the left end portions of walls **26a** of lever **26** which portions and side walls are connected by pin **29**. It will be noted that walls **28a** are cut away beneath the pin **17** sufficiently to clear the latter as the lever **28** moves vertically.

The narrowed end of main lever **28** terminates in a vertical lip **28b** for engaging the adjustable temperature cam **30** mounted on shaft **31** and movable by means of the calibrated knob **32**. A centrally depressed portion of main lever **28** is apertured to receive the ball **33** which projects slightly through the former into contact with block **9** where it is maintained by follow-up spring **34** fixed to lever **28** at **35**. Proper relative positioning of the levers and switch arms is aided by a coil spring **36** centered on a projection on lever **26** and a similar provision on follow-up spring **34**; coil spring **37** between lever block **19** and the short arm of lever **26** insures proper contact pressure between contacts **24** and bar **25**.

Flexible connectors **38** unite switch arms **23** to pin connectors **39** which extend through the insulated housing closure block **1a**; the latter connectors are electrically connected to spaced conductor strips **40** having lug screws **41** for connection in the electric power circuit to the range heater coil.

The operation of this form of my invention is as follows: With the component parts in the relation shown in Fig. 1 wherein diaphragm **13** is filled with fluid in the minimum throw position of the cam **15**, feeler member **11** is filled with fluid at a relatively low temperature, at least lower than the lowest possible setting of the range cam **30**, conduit **10** and its branches are filled; diaphragm **5** hence is in its collapsed position virtually empty of fluid; lip **28b** of lever **28** is in engagement with the low temperature portion of cam **30**, and with the contacts **24**, **25** in engagement, the stop screw **20** is engaged by a screw driver through an aperture (not shown) in housing **1** and is retracted just sufficiently to insure that said contacts remain closed as the cam **15** rotates 180 degrees to **75**

its high position. As the latter action takes place, the fluid in diaphragm **13** will be forced into diaphragm **5** expanding the latter and thereby raising the left end of lever **28** about the low temperature point of cam **30** as a fulcrum. Since the stop screw **20** in its adjusted position is ineffective to separate switch arms **23** and lever **26**, these parts will oscillate as a unit about the pivot pin **17**. Thus, the electrical circuit to the range is maintained as long as the fluid transfer to the diaphragm **5** originates only in the diaphragm **13**. However, as soon as the feeler member **11** heats up due to receiving heat from the heated pan, for example, the expansion of the fluid therein is superposed on that from the diaphragm **13** so that the clockwise arcuate movement of the lever **26** about the pin **17** exceeds that permitted the lever **23** by the stop screw **20** and therefore, the contacts **24**, **25** are opened. As the cycling fluid returns to the diaphragm **13**, lever **26** moves in a counterclockwise direction to close the contacts **24**, **25**. It will be observed that rotation of the range cam **30** to its high temperature position will raise the fulcrum for the main lever **28** so that for the adjustment of stop screw **20** previously described a higher temperature of feeler member **11** and hence greater expansion of its contained fluid will be required to expand diaphragm **5** sufficiently to separate the contacts **24**, **25** and open the circuit to the heater.

Stop screw **20** is adjusted at the factory as follows: With the power source disconnected from terminals **41**, the low temperature portion of cam **30** engaging lip **28b** and the cam **15** stopped in its maximum diaphragm compressing position, the feeler member **11** is heated to a temperature slightly below the lowest temperature setting of the temperature adjustment knob **32** and the screw **20** adjusted until the contacts **24**, **25** are just opening.

The arrangement of the fluid-filled components of the cycling system of Fig. 1 permits the location of the switch and its control knob **32** in the usual control panel position on the range with the diaphragm **13**, cam **15** and its driving motor located at any convenient and relatively cool place in the range enclosure such as near the base thereof. In the embodiment of Fig. 1, furthermore, several diaphragms such as **13** corresponding to the number of burners of the range may be spaced about the cam shaft **16** for compression by the same cam **15**.

The arrangement of Fig. 1 may be modified by employing in lieu of the single chambered diaphragm **5** specifically shown in this figure, a diaphragm having a rigid dividing wall between the similarly shaped upper and lower walls thereby dividing the diaphragm interior into upper and lower separated chambers. Such a diaphragm is shown in my co-pending application Serial No. 600,862 filed June 22, 1945, and entitled: Corrugated Diaphragms now Patent No. 2,487,947. By connecting the branch **10b** from the diaphragm **13** into the upper nipple block leading into the upper chamber and connecting the branch **10a** from the feeler member **11** to the conduit **10** as in Fig. 1 and thence to the lower chamber, a thermally inert fluid might be used as the periodically circulated medium with the consequent advantages of ambient stability. Also a single large diaphragm **13** would suffice for several heater plates.

It will be apparent that various forms of feeler member **11** may be employed in the system of Fig. 1 subject only to the limitation that the liq-

uid within the conduit 10a be forced to the left or right dependent on the temperature of the feeler member. Thus, the latter may constitute with conduit 10a a continuous chamber filled with thermo-expansive liquid. Alternatively, element 11 may be filled with such a fluid and the conduit 10a filled with an ambiently stable, incompressible liquid, the two fluids being separated by a flexible wall within the element 11 as shown in my copending application, Serial No. 599,383 filed June 14, 1945, and entitled Thermal Responsive Device and Mounting Therefor, now Patent No. 2,487,946.

Figs. 3, 6 and 7 show a variation of the system of Fig. 1 wherein the cyclic expansion of diaphragm 5 is effected not by the circulation of fluid due to the action of a rotated cam upon a fluid-connected diaphragm, but by the periodic heating and cooling of a fixed volume of fluid contained within the heater and the diaphragm. In these figures the feeler member 11 has fluid pressure connection to diaphragm 5 through conduit 10a and hence exerts lifting force on block 9 as the temperature of the former is raised. Between block 9 and the main lever 28 is provided an electrically operated, self-contained cycling unit which includes an elongated supporting lever 42 having a reversely bent portion provided with an electrical contact 43. The opposite end of lever 42 is provided with a block 44 of insulating material secured thereto by screws 45 which may extend also through an insulating and reenforcing plate 46 as shown in Figure 3. Block 44 is laterally apertured to receive a hinge pin 47 which also extends through similar apertures in a pair of parallel ears 48 closely fitting the ends of said block. Ears 48 are preferably formed as welded projections of the main lever 28 and serve as a laterally stable mounting for the hinge pin 47 and the confined block 44. Screws 49 extending into the block 44 from above secure an electrical connector plate 50 and an elongated strip of spring metal 51 thereto. Spring strip 51 serves as a support for an elongated switch arm 52 to which it is riveted at 53 and permits said arm and its contact 52a to be moved downwardly upon the upward movement of the right end of a loop spring 54, the left end of which is apertured to receive a hook projecting from one end of a slot 55 formed in switch arm 52. As shown the apertured right end of spring 54 receives the hooked end of a projection 56 carried by main lever 28 but insulated therefrom by suitable strips 57. Centrally of the lever 42 is mounted by means of a nut 59 a stud 58 to the lower end of which is fixed a button 60 of suitable rigid insulating material which is arranged to continuously engage block 9 during the operation of the switch. Resting on a sheet of electrical and thermal insulating material 61 is a coil of thin-walled tubing made of electrical resistance material having one end sealed as at 62 and the other end connecting with a suitable central bore in the stud 58. The lower wall of a diaphragm 5c is suitably fixed to the top of stud 58 and is apertured in line with said bore to enable expansion fluid from the latter to enter and expand the diaphragm following connection of leads 50a and 62a to a source of electrical current and a closed condition of contacts 43 and 52a. The path of the electric current through the contacts 43, 52a is seen to be through the upper lead to electrical connector plate 50, metal strip 51, switch arm 52, contacts 52a, 43, lever 42, nut 59, stud 58, the

coiled tubing 62 to lead 62a. The diaphragm-heater assembly of Figs. 3, 6 and 7 is not claimed herein, in as much as it is fully described and claimed in my copending application Serial No. 600,862 supra.

The upper wall of diaphragm 5c has centrally secured thereto the tapered stud 58a adapted to continuously engage a contact ball 63 such as a vitreous bead, held in a suitably tapered aperture in the main lever 28 by spring 34. Adjustment screw 64 threaded in a block 65 of insulating material secured to the lever 42 serves as a lower stop for the spring mounted lever 52 as it snaps to its lower position and provides means for varying the on-off cycle.

The operation of this embodiment of my invention will, it is thought, be apparent from the foregoing. The diaphragm 5c with its associated heater, lever and switch elements provides the same cycling deflections for lever 28 as is provided by the driven cam 15 and diaphragm 13 of Fig. 1; adjustment of this form of my invention is carried out in the same way as in the arrangement shown in Figs. 1 and 2. Now visualizing the complete switch of Fig. 3 as constituting the switch components of Fig. 1 modified by substituting the Fig. 3 structure for the lever 28 and all parts therebelow, shown also in Figs. 6 and 7, it will be apparent that the periodic heating and cooling of diaphragm 5c and its consequent expansion and contraction will raise and lower the left end of lever 28 with a periodicity dependent on the heat capacity of the diaphragm and the adjustment of screw 64. This will be evident since the right end of lever 42 is hinged to lever 28 and the distance between the ball 63 and the button 60 increases as the diaphragm 5c expands due to heat produced by the electric current flowing through the tube 62. As the left end of lever 28 is moved upwardly, projection 56 is carried upwardly also to such a point that the loop spring 54 snaps the switch arm 52 downwardly against the stop 64 thus opening the electrical contacts 43, 52a and allowing the diaphragm to cool and contract and the left end of lever 28 to fall and thus approach the lever 42. When diaphragm cooling has brought levers 28 and 42 together sufficiently to enable the projection 56 to swing the spring 54 to contact closing position, the electric circuit to the tube 62 will again be closed and the cycle will continue indefinitely.

It will be observed that the action of the heated diaphragm corresponds to that of diaphragms 5 and 13 and the cam 15 of Fig. 1. The fluid pressure transmitted by the feeler element 11 due to heating expands diaphragm 5 (Fig. 3) and therefore acts to raise the left end of lever 28 and separate contacts 24—25 controlling the energization of the range heater element until such contacts are closed for only such a fraction of the operative cycle of the diaphragm 5c-heater 62 unit as will supply a quantity of heat equal to that dissipated by the cooking vessel, i. e., a stable heat transfer condition. In addition to the elimination of the motor and its cycling cam 15, the diaphragm 13 and necessary tubing, the Figs. 3, 6 and 7 embodiment is quite compact and is cheaper to manufacture than the first-described form of my invention.

In Figs. 4 and 5 there is shown an extremely compact switch which may be most advantageously used in the system of Fig. 1, by merely substituting the more compact switch and housing for the housing 2 and its switch structure (Fig. 1). Another feature of this switch is in the provision

of an adjustable stop for varying the relation of the main lever and the range cam. In Figs. 4 and 5 a housing 66 closed by a top wall 67 and end wall 68 of insulating material is secured to the range panel 69 by suitable means such as screws 70. The left end of the housing 66 is provided with an elongated block 71 of insulating material which is held in place by one or more recessed screws 72, and carries on its vertical face a spaced pair of riveted or otherwise connected spring strips 73. A laterally extending, elongated block 74 of insulating material serves to bridge by means of the connecting means 75, the upper ends of the spring strips 73 and carries on its upper surface a pair of spaced contact arms 76, 77 bearing contacts 78, 79 respectively at the outer ends thereof. A spring contact arm in the form of a flat strip 80 has one end fixed to the top middle portion of the block 71 by means such as screw 81 and extends beneath the block 74 to which it is anchored as by a rivet 82 extending through the strip and block and terminating in a head 83 in a recess provided in the latter. A coil spring 84 disposed between the top wall 67 and the block 74 serves to flex the spring strip 80 downwardly against the vertex of a generally triangular lever 85 the opposite ends 86 of which are snaped over suitable hinge-forming projections 87 extending from the side walls of the housing 66. A projection 88 formed centrally of the lever 85 is adapted to transmit the pressure of spring 84 to the block 98 of diaphragm 5.

The right end of spring strip 80 carries in suitable insulating relationship a bridge member 89 secured thereto at 89a and having contacts 91 adapted to engage contacts 78, 79, respectively as shown in Fig. 4. Strip 80 is reenforced by a stiff strip 92 riveted thereto at 89a and 93 and having a downwardly offset cam-engaging end which is adapted to be bent upwardly against an adjustable abutment such as the cam 94 of the range knob 95 by means of the screw 96 threaded through bracket 97 welded to the offset end. Leads 90 connect the ends of switch arms 76, 77 with terminal strips 99 as will be apparent from Figures 4 and 5.

Zero adjustment of the switch of Figs. 4 and 5 is easily made following the procedure already described, the coarse adjustment being effected through positioning of the cam 94 prior to tightening of its retaining screw, followed by necessary movement of screw 96 which is accessible from the switch exterior by means of a suitable opening (not shown) in the housing 66. In operation the cycling travel of the block 98 of diaphragm 5 is such that separation of contacts 78, 79 and 91 does not result from engagement of the right end of strip 92 with the cam 94, strip 80 merely flexing and the arms 76, 77 moving with it. When the feeler member pressure is superimposed on the cycling pressure, however, the movement of block 98 is sufficient to flex strip 80 to such an extent that the block 74 is moved upwardly and to the left and the arms 76 and 77 are moved away from the strip 90 and strip 92 with consequent opening of the contacts.

The spring-hinged modification of Figs. 4 and 5 provides in compact form the same operating advantages of the Figs. 1 and 2 construction and in addition eliminates the friction, lost motion and misalignment of parts inherent in greater or less degree in all pivoted lever systems.

While I have shown and described certain preferred embodiments of my invention, it will be

understood that I do not intend to be limited thereto, but only as may be within the scope of the following claims.

I claim:

5. A fluid-pressure cycling system for electric heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing liquid thereinto and withdrawing the same therefrom, and a switch having a pair of contact-carrying arms which are relatively movable to open and close the contacts thereof and one of which arms is disposed in pressure-receiving relation with said expansible chamber means and thereby movable with respect to the other of said arms whereby the relative positions of said contacts at any selected instant during the cyclic expansion of said expansible chamber is dependent on the temperature of said temperature-responsive member.

2. The combination set forth in claim 1 in which there is further provided cam means also disposed in pressure-receiving relation with said expansible chamber means and in pressure-transmitting relation with one of said arms for modifying the effect of said last means upon said last named arm.

3. The combination set forth in claim 1 in which the fluid displacement characteristics of said fluid circulating means are so chosen with reference to those of said member and also the volumetric capacity of said diaphragm means that said contacts remain in one of said positions during the cyclic operation of said fluid circulating means alone but move to the other of said positions upon the further expansion of said diaphragm means by heating and resultant expansion of said member.

4. A fluid-pressure cycling system for electric heaters comprising expansible chamber means, a temperature-responsive, hollow member coupled to said means to constitute therewith a continuous enclosure, a thermo-expansive fluid filling said enclosure, cyclicly operated fluid circulating means located remote from said first means and fluid coupled thereto for forcing liquid thereinto and withdrawing the same therefrom, and a switch having a pair of contact-carrying arms which are mounted for relative movement to effect an open and a closed position, respectively, of said contacts and also movable in unison during a closed position interval of said contacts and one of which arms is disposed in pressure-receiving relation with said expansible chamber means and thereby movable with respect to the other of said arms, the fluid displacement characteristics of said fluid circulating means being so chosen with reference to those of said member and the volumetric capacity of said first means that said contacts remain closed during the operation of said fluid circulating means alone, but move to an open position upon the further expansion of said first means by heating and consequent expansion of said member.

5. The combination set forth in claim 4 in which there is further provided an adjustable abutment also disposed in pressure-receiving relation with said expansible chamber means and in pressure-transmitting relation with one of said arms for modifying the effect of said chamber means upon said one arm.

6. A fluid-pressure cycling system for electric

heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing liquid thereinto and withdrawing the same therefrom, a plurality of pivoted, contact-carrying switch arms spring-biased to closed-contact position and a lever carried by one of said switch arms and disposed between the latter and said chamber means and adapted to transmit the pressure of the latter to said arms to move said arms synchronously with the operation of said fluid circulating means and to effect opening and closing of said contacts in response to the temperature of said member.

7. A fluid-pressure cycling system for electric heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing liquid thereinto and withdrawing the same therefrom, a plurality of pivoted, contact-carrying switch arms spring-biased to closed-contact position and a lever carried by one of said switch arms and disposed between the latter and said chamber means and adapted to transmit the pressure of the latter to said arms to move said arms synchronously with the operation of said fluid circulating means and to effect opening and closing of said contacts in response to the temperature of said member.

8. A fluid-pressure cycling system for electric heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing liquid thereinto and withdrawing the same therefrom, a plurality of contact-carrying switch arms disposed for relative, contact-opening movement and also unitary, closed-contact movement, means for effecting said movements including a pressure-transmitting member disposed between said first means and said arms, and a stationary abutment having an adjustable, intercepting position with respect to said last means and said arms, whereby the duration of the open-contact condition of said arms will be dependent on the temperature of said member and the position of said abutment.

9. A fluid-pressure cycling system for electric heaters comprising a casing, expansible chamber means mounted therein, a temperature-responsive hollow member outside said casing and forming with said chamber a fluid-tight enclosure, a thermo-expansive fluid filling the latter, an adjustable cam and a plurality of contact-carrying switch arms mounted in pressure-transmitting relation therewith within said casing and disposed in pressure-receiving relation with said chamber means, and a cyclicly operated, corrugated diaphragm disposed to exert cyclicly additive pressure on said cam and contact-carrying switch arms whereby the contacts of the latter will be cyclicly opened and closed in response to the total pressures exerted by said fluid and said diaphragm.

10. A fluid-pressure cycling system for electric heaters comprising a casing, a corrugated diaphragm mounted therein, a temperature-responsive, hollow member outside said casing and forming with said diaphragm a fluid-tight enclosure, a thermo-expansive fluid filling the latter, an adjustable cam and a plurality of contact-carrying switch arms mounted in pressure-transmitting relation in said casing, a lever having one end fulcrumed on said cam and the other end pivotally connected to one of said arms and in pressure-transmitting relation with said diaphragm and adapted to transmit the pressure of the latter to said cam and arm and a cyclicly operated diaphragm fluid-coupled to said enclosure to exert additive pressure on said first-mentioned diaphragm whereby the contacts of said switch arms will be cyclicly opened and closed in response to the total pressure transmitted by said fluid.

11. A fluid-pressure cycling system for electric heaters comprising a casing, expansible chamber means mounted therein, a temperature-responsive, hollow member outside said casing and forming with said chamber a fluid-tight enclosure, a thermo-expansive fluid filling the latter, an adjustable cam and a plurality of contact-carrying switch arms mounted in said casing, a lever having one end fulcrumed on said cam and the other end pivotally connected to one of said arms and disposed in pressure-transmitting relation with said chamber means and adapted to transmit the pressure of the latter to said cam and arm, an expansible chamber filled with a thermo-expansive fluid and disposed between said first chamber and said lever, and cyclicly energized, electrical heating means for said last chamber whereby the additive pressures of said chambers will be transmitted to said switch arms to cyclicly open and close the contacts thereof.

12. A fluid-pressure cycling system for electric heaters comprising a casing, expansible chamber means mounted therein, a temperature-responsive, hollow member outside said casing and forming with said chamber a fluid-tight enclosure, a thermo-expansive fluid filling the latter, an adjustable cam and a plurality of contact-carrying switch arms mounted in said casing, a lever having one end fulcrumed on said cam and the other end pivotally connected to one of said arms and disposed in pressure-transmitting relation to said chamber means and adapted to transmit the pressure of the latter to said cam and arm, an expansible chamber filled with a thermo-expansive fluid and disposed between said first chamber and said lever, a tubular heater of electrical resistance material located beneath said chamber and forming a continuous enclosure therewith, a thermo-expansive fluid filling said enclosure and an electrical circuit for said heater which is cyclicly energized thereby for producing a cycling pressure in said last chamber which is added to that of the first chamber to cyclicly open and close the contacts carried by said switch arms.

13. A fluid-pressure cycling system for electric heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing fluid thereinto and withdrawing the same therefrom, a plurality of contact-carrying switch arms arranged to be moved in unison to maintain the

closed condition of said contacts in response to the cyclic expansion of said chamber means by said circulating means or relatively to each other to open said contacts when said chamber means further expands due to the attainment of an elevated temperature in said hollow member and an adjustable abutment disposed in the path of movement of one of said arms for blocking the movement of the latter to establish an open-contact position from which the remaining arms are moved upon the further expansion of said chamber.

14. A fluid-pressure cycling system for electric heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing fluid thereinto and withdrawing the same therefrom, a plurality of contact-carrying switch arms arranged to be moved in unison to maintain the closed condition of said contacts in response to the cyclic expansion of said chamber means by said circulating means or relatively to each other to open said contacts when said chamber means further expands due to the attainment of an elevated temperature in said hollow member, an adjustable abutment disposed in the path of movement of one of said arms for blocking the latter to establish an open-contact position from which the remaining arms are moved upon the further expansion of said chamber means, and adjustable means carried by said one arm for deforming the latter to vary its interval of blocking by said abutment.

15. A fluid-pressure cycling system for electric heaters comprising expansible chamber means, a temperature-responsive hollow member coupled to said means to constitute a continuous enclosure, a thermo-expansive fluid filling said enclosure, fluid circulating means also connected to said chamber means for cyclicly forcing fluid thereinto and withdrawing the same therefrom, a support bearing a plurality of normally disposed spring strips, a second support carried by said strips, a plurality of contact-carrying switch arms disposed on either side of said second support and arranged to be moved in unison to maintain the closed condition of said contacts or relatively to each other to open said contacts and an adjustable abutment disposed in the path of movement of one of said arms for blocking the latter to thereby open said contacts upon the attainment of an elevated temperature in said hollow member.

16. A fluid-pressure cycling system for electric heaters comprising expansible chamber means, a temperature-responsive, hollow member coupled to said means to constitute a continuous enclosure, a thermo-expansive fluid filling said enclosure, fluid circulating means also connected to said chamber means for cyclicly forcing fluid thereinto and withdrawing the same therefrom, a support bearing a plurality of normally disposed spring strips, a second support carried by said strips, a plurality of contact-carrying switch arms disposed on either side of said second support and arranged to be moved in unison to maintain the closed condition of said contacts or relatively to each other to open said contacts, an adjustable abutment disposed in the path of movement of one of said arms for blocking the latter to thereby open said contacts upon the attainment of an elevated temperature

in said hollow member, and adjustable means carried by said arm for deforming the latter to vary its interval of blocking by said abutment.

17. A fluid-pressure cycling system for electric heaters comprising expansible chamber means, a temperature-responsive, hollow member forming with said chamber a fluid-tight enclosure, a thermo-expansive fluid filling the latter, a support having a plurality of normally disposed spring strips, a second support carried by said strips, a plurality of contact-carrying switch arms disposed on either side of said second support and arranged to be moved in unison to maintain the closed condition of said contacts or relatively to each other to open said contacts and an adjustable abutment disposed in the path of movement of one of said arms for blocking the latter to thereby open said contacts upon the attainment of an elevated temperature in said hollow member.

18. A fluid-pressure cycling system for electric heaters comprising expansible diaphragm means, a temperature-responsive, hollow member coupled to said means to constitute a continuous enclosure, a thermo-expansive fluid filling said enclosure for transmitting pressure to said means upon heating of said member, fluid circulating means also connected to said diaphragm means for cyclicly forcing fluid thereinto and withdrawing the same therefrom, a switch including a plurality of relatively movable, contact-carrying arms having a closed contact position and an open contact position, spring means disposed to urge said arms into one of said positions and means disposed between said diaphragm means and said arms for transmitting pressure from the former to the latter for moving said switch arms into the other of said positions in response to heating of said member.

19. A fluid-pressure cycling system for electric heaters comprising expansible diaphragm means, a temperature-responsive, hollow member coupled to said means to constitute a continuous enclosure, a thermo-expansive fluid filling said enclosure for transmitting pressure to said means upon heating of said member, fluid circulating means also connected to said diaphragm means for cyclicly forcing fluid thereinto and withdrawing the same therefrom, and a switch including a plurality of relatively movable, contact-carrying arms having a closed contact position and an open contact position, spring means disposed to urge said arms into closed contact position and means disposed between said first means and said arms for transmitting pressure from the former to the latter for moving said arms to open contact position in response to heating of said member.

20. A fluid-pressure cycling system for electric heaters comprising expansible chamber means, a temperature-responsive, hollow member coupled to said means to constitute a continuous enclosure, a thermo-expansive fluid filling said enclosure, fluid-circulating means also connected to said chamber means for cyclicly forcing liquid thereinto and withdrawing the same therefrom, a plurality of pivoted, contact-carrying switch arms spring-biased to closed contact position, and a lever disposed between one of said arms and said chamber means and adapted to transmit the pressure of the latter to said arms to move said arms synchronously with the operation of said fluid-circulating means and to effect opening and closing of said

contacts in response to the temperature of said member.

21. A fluid-pressure operated, adjustable switch comprising a housing, an expansible chamber having a conduit adapted to be connected to an external source of fluid pressure, an adjustable abutment carried by said housing and spaced from said chamber, an elongated, contact-carrying switch arm having one end resiliently mounted with respect to said housing and remote from said abutment and having an opposite end portion adapted to be intercepted by the latter, said portion being adjustably deformable toward and away from said abutment and independently thereof, said arm having also an intermediate portion disposed in pressure receiving relation with said chamber, and a second contact-carrying switch arm resiliently mounted with respect to said housing and movable from a closed-contact position with said first arm to an open contact position away from the latter as said chamber expands and said first arm moves to its abutment-intercepted position.
